SAND TESTING DEVICE FOR OIL WELLS

Filed Oct. 29, 1927

UNITED STATES PATENT OFFICE

DOUGLAS B. FOWLER AND JOHN R. FOWLER, OF OLNEY, TEXAS

SAND-TESTING DEVICE FOR OIL WELLS

Application filed October 29, 1927. Serial No. 229,765.

This invention relates to improvements in means for ascertaining the value of a partly drilled well, especially an oil well, and the object of the invention is to provide an attachment for the drill stem for testing the sand at the bottom of the partly drilled hole.

Without the use of a sand tester it is necessary to set the well casing and cement it, both at considerable expense, and then wait several days for the cement to set, after which further delay is experienced in bailing the mud and water from the hole to get the pressure off the sand.

In the present invention the sand tester is attached to the end of the hollow drill pipe or drill stem and rotated to a seat, the result being that the device at once cuts off all mud and water pressure on the sand, and the sand at the bottom of the hole can then be taken out to test the value of the well.

The invention will be readily understood from a perusal of the following detailed description, taken in connection with the accompanying drawings, forming part of this specification, and in which:

Figure 1 represents a longitudinal sectional view of the sand tester.

Figures 2, 3, 4 and 5 are cross-sectional views thereof, taken respectively along the lines corresponding with the views.

Referring more particularly to the drawings, 1 denotes the body of the sand tester which is hollow and screw-threaded at both ends. The upper end has a cap or covering 2, interiorly threaded and advanced down upon the body 1, and has a neck 3 the neck being channeled and provided with a shoulder 4, the channel or opening being indicated at 5. The lower end of the body 1 is provided with a shoe 6, flared slightly outwardly and threaded onto the body as shown.

On the interior of the body and occupying the central part thereof is a tubular element 7 provided with a removable lower closure cap 8. The upper end of this tubular element 7 is threadedly seated in the shoulder 4 of the cap 2.

In the channel or opening 5 of the neck 2 of the closure or cap is inserted a tubular member 9 which is longitudinally grooved on

opposite sides at 10 and the neck 3 is longitudinally ribbed at 3^a, providing a key-way and the upper end of the tubular member is threaded at 11 for attachment to the drill stem of the well rig. Seated in the lower end 55 of the tubular member 9 is a smaller tube 12 and which depends within the element 7 to about midway thereof. On the tube 12 are pistons 13, 14 and 15 provided with piston rings 16, the lower piston being removably 60 attached to the end of the tube 12 and including a projection 17 for seating a spring 18. The lower end of this spring rests upon the cap 8. It will be observed that the pistons are spaced apart on the tube 12 and tightly 65 fit the tubular element 7.

Both the tubular element 7 and the tube 12 are perforated at 19 and 20 for the purpose of permitting the fluid or gas in the well to enter after the tester is set in and opened at the 70 bottom of a well.

In the operation of the attachment, after drilling a well down to a point where substance is encountered and where the operator believes there is oil or gas sand, the drill is 75 removed and the sand tester is attached to the drill stem, which is then lowered into the hole. After lowering to its seat, the drill stem is given a turn with chain tongs or rotary backward say five-eighths of an inch, full turn of 80 whole string of pipe or drill stem line. This movement will register the ribs 3^a with the longitudinal grooves 10 of the key-way. The drill stem is then lowered approximately twenty inches and the perforations in the tube 85 12 will register with the perforations 20 in the member 7 so as to thereby allow contents of the sand to flow into the drill pipe. With the shoe 6 resting on the strata in the bottom of the hole, the casing 1 effectually shuts off 9 mud and water from the strata to be tested, preventing entrance thereof to the sand tester. Piston 13 prevents fluid above the tool from entering, while piston 14 acts to prevent entrance of fluid which may seep through past 95 piston 13. The piston 15 acts as a bottom seal for the contents of tube 12. The sand tester is then allowed to set for any length of time desired, after which the drill pipe is pulled upward twenty inches, and the sand 100

tester closes, retaining the contents of sand already taken in. The drill stem and tester are then removed from the hole. The contents can then be taken out of tester and the value of the hole ascertained.

5 The invention is not to be understood as limited to the specific construction here shown, but is capable of minor modifications, such changes and alterations to come within 10 the scope and meaning of the appended claims.

What is claimed is:

1. A sand tester for oil wells, comprising a hollow cylindrical body, a cap on one end 15 with an opening in the cap, a collar on the opposite end of the body; a tubular element removably attached to the cap on the inside of the cylindrical body and depending centrally of said body to approximately the lower 20 end thereof; a tube disposed in said tubular element and pistons spaced on the tube and arranged to reciprocate within said tubular element; said tube and tubular element being perforated, the perforations registerable with 25 one another to permit sand to enter.

2. A sand tester as set out in claim 1, and wherein said cap has a neck with an opening, the opening having ribs; and a relatively short tubular member receivable in said opening, said relatively short tubular member having channels, said channels and said ribs forming a key-way; said tube carrying the pistons removably connected to said relatively short tubular member, the pistons and tube 30 reciprocating within said tubular element in creating a vacuum in the lower end of the tester.

3. A sand tester for oil wells as set out in claim 1, said tubular element having a removable cap on its lower end to close the 40 end; a spring inside the tubular element, the upper end of the spring having its seat on the lowermost of said pistons, said spring forming a cushion.

45 In testimony whereof we affix our signatures.
